UNITED STATES PATENT OFFICE.

GUSTAF A. WALLIN, OF SCOTCH PLAINS, NEW JERSEY, ASSIGNOR TO A. KIMBALL COMPANY, OF NEW YORK, N. Y., A CORPORATION OF NEW YORK.

PIN-TICKET.

1,235,618.

Specification of Letters Patent.

Patented Aug. 7, 1917.

Application filed January 21, 1916. Serial No. 73,465.

To all whom it may concern:

Be it known that I, GUSTAF A. WALLIN, a citizen of the United States, and resident of Scotch Plains, county of Union, State of New Jersey, have invented an Improvement 5 in Pin-Tickets, of which the following description, in connection with the accompanying drawing, is a specification, like characters on the drawing representing like

10 parts.

This invention relates to improvements in pin tickets and has for its object the production of a convenient and useful ticket for marking fabrics, garments and the like with 15 the price, quality, or such other information as may be desired, the ticket being so constructed that it may be applied to the face of the fabric without folding over the edge thereof and when applied may be provided 20 with a sealing device which cannot be removed without the mutilation or practical destruction of the sealing device.

The purpose of this invention is to provide a pin ticket which cannot be removed 25 from the article without destruction so that it may be applied to goods which may be sent out upon approval, it being the custom of merchants to refuse to credit returned articles if they show indications of use 30 which would readily be observed by the removal or mutilation of the ticket.

A "security" ticket of this general character is disclosed in Patent No. 1,054,927 granted March 4, 1913 to Marsh and Wal- 35 lin, said ticket being so constructed as to fold over the edge of the article to which it is applied.

In many instances however, it is desirable that a "security" ticket of this character be 40 applied to the face of the article at a distance from the edge thereof and the present invention is intended to supply this need.

This is accomplished by providing a card having a fastening member preferably in 45 the form of a staple adapted to be thrust through the article to be marked or a portion thereof, the staple also being thrust through an independent sealing device and its prongs turned down upon the face there- 50 of, the sealing device being provided with a flap adapted to be folded over the bent down prongs of the staple and secured closely against them by a permanent locking means such as one or more eyelets located in prox- 55 imity to the staples.

When the staple is thus secured the ticket cannot be removed without the mutilation or practical destruction of the sealing device.

A preferred embodiment of the invention is illustrated in the accompanying drawings 60 in which,

Figure 1 is a view of the face of the ticket showing the same applied to the side of a piece of fabric or other article,

Fig. 2 is a view of the opposite side of the 65 fabric showing the sealing member in extended position and illustrating in dotted lines the position of the exposed ticket which bears the identifying marks in dotted lines,

Fig. 3 is a similar view showing the sealing member locked by a pair of eyelets, and,

Fig. 4 is a vertical longitudinal sectional view through a ticket and the sealing member and the article to which it is attached.

The marking device illustrated herein 70 comprises a card 1 adapted to bear identification marks, price marks, etc., having a penetrating member which preferably is in the form of a staple 2 affixed to the card adjacent to the edge thereof having its 80 prongs 3, 4, provided with perfect conoidal points, passing through the card and an intermediate portion 5 bent over the edge of the card to retain the prongs of the staple substantially at right angles to the reverse 85 face of the card as is usual in the well known "Empire" form of ticket.

It will however be understood that the manner of attachment of the penetrating device to the card is immaterial so far as 90 the present invention is concerned.

The sealing member preferably is in the form of a strip of thin material such as paper, cardboard, celluloid or a non-corrodible metal preferably having a transverse line or crease 6 dividing the strip into two flaps 7 and 8 adapted to be folded about the transverse crease 6 so that the flaps may be closely superposed.

One of the members 8 of the sealing mem- 100 ber preferably is provided with apertures 9, 10 adapted to receive the prongs of the staple but if the material of which the strip is made is easily penetrable these apertures may be omitted. The flaps 7 and 8 desirably are provided with apertures 11 and 12 disposed symmetrically in respect to the transverse crease so that when the flap 7 is folded down upon the flap 8 the apertures 11 105 and 12 will be superposed upon the apertures 11 110

The flaps may then be secured together permanently by locking members 13 which conveniently may be in the form of eyelets, rivets or like devices having flanges 14, 15 5 adapted to be pressed against the outer sides of the flaps 7 and 8 to increase the stiffness of the flaps as well as to form a positive means for preventing the separation of said flaps.

- 10 In use, the card 1 is first placed against the outer side of the fabric A or other article to be marked and the prongs 3 and 4 thrust through the article, the sealing member is then pressed over the extended prongs, 15 the prongs 3, 4 of the staple 2 passing through the apertures 9, 10, of the flap 8 if such apertures be provided or thrust through the body of the same and turned down firmly against the face of said sealing member.
- 20 The flap 7 is then folded down upon the flap 8 and the eyelets 13 inserted through the superposed apertures 11 and 12 and clenched in the usual manner.

In the preferred form of the invention 25 illustrated herein two eyelets are used to secure the flaps 7 and 8 together, said eyelets being located in such proximity to the prongs of the staple that the flaps cannot be separated sufficiently to permit the withdrawal of the staple without mutilating or 30 practically destroying the sealing member.

While the particular embodiment of the invention illustrated herein shows two co-operating flaps, it will be obvious that a 35 greater number of flaps may be used and also that the locking members may be disposed in different relation to the staple than illustrated herein.

It will also be understood that different 40 locking means may be provided within the spirit and scope of the following claims.

Copies of this patent may be obtained for five cents each, by addressing the "Commissioner of Patents.
Washington, D. C."

Having thus described my invention what I claim as new and desire to secure by Letters Patent is;

1. A marking device for fabrics and the like comprising a card having a staple adapted to be thrust through the article to be marked, an independent sealing member comprising a penetrable portion through which the prongs of the staple may be 45 thrust and bent down thereupon and a covering flap adapted to be folded down upon the penetrable portion to cover the shanks of the staple and fastening means adapted positively to engage the superposed portions 50 of the sealing member in proximity to said penetrating member and permanently to lock the same together, whereby the removal of the marking device without mutilation of the sealing member is prevented. 55

2. A marking device for fabrics and like articles adapted to be secured thereto at a distance from the edge comprising a card having a staple adapted to be thrust through the article to be marked and an independent 60 sealing member transversely creased to present two flaps adapted to be superposed, one of said flaps being apertured adjacent to said crease to receive the prongs of the staple and to permit the same to be bent down thereupon, said flaps being provided with apertures adapted to be superposed in proximity to said staple whereby when said flaps are folded together and eyelets passed 65 through said apertures the flaps are secured 70 permanently together and removal of the marking device without mutilation of the sealing member is prevented. 75

In testimony whereof, I have signed my name to this specification.

GUSTAF A. WALLIN.
